UNITED STATES PATENT OFFICE.

JOHN A. GOODWIN, OF NEW YORK, N. Y.

MECHANICAL TOY.

SPECIFICATION forming part of Letters Patent No. 417,637, dated December 17, 1889.

Application filed April 19, 1889. Serial No. 307,653. (No model.)

To all whom it may concern:

Be it known that I, JOHN A. GOODWIN, a subject of the Queen of Great Britain, residing at New York, county and State of 5 New York, have invented a new and useful Mechanical Toy, of which the following is a specification.

My said toy consists, essentially, of a board or plane surface having perpendicular sides 10 and extending across it a fence or partition provided with an opening or openings, a spring-propelled catapult which may be made to represent the moving part of a figure or animal, while the fixed part may be permanently attached to or be simply pivoted on 15 the board, and, finally, a ball or missile intended, when struck by the said lever or catapult, to be projected through such opening or openings. The ball or missile may be either 20 tethered to the board or left loose.

Referring to the accompanying drawing, which forms a part of this specification, the figure therein shown represents a perspective view of the toy, the broken lines representing the lever, catapult, animal, or figure 25 in its extended or discharged position, and the thick lines in their pulled-back position ready for striking.

1 represents a board, which may have the 30 rectangular form shown or have a circular or other form. Said board has marginal sides or rails 2, and is at one part crossed by a fence 3, which has one or more openings or 35 passage-ways 4 for the transit of a ball or missile 5, preferably of spherical shape.

6 is a lever or catapult, representing in this 40 case the hind portion of a donkey, which may be of wood, and which is pivoted to the board 1 at 7, and is limited to the pre-scribed vibration by a projection 8, which traverses a slot 9 in the board, or by any suitable means. The catapult is drawn to the 45 projected position (see dotted lines 10) by a spring—such as an india-rubber band 11—secured to projection 8 and a part of the board, and is capable of being caught and held at the retracted position shown in the strong lines of the figure by a catch or trigger 12, whose spring 13 retracts it against a 50 stop 14.

The catapult in the drawing herewith rep-

resents the hind part of an animal—say a donkey—whose front part is printed or painted upon the board. The ball 5 is preferably tethered or moored to the board by a piece 55 of thread or an india-rubber thong 13.

The herein-described form of my invention is susceptible of various modifications, which are included. For example, a spiral or other metallic spring may be substituted for the 60 rubber band. The lever or catapult may be made to represent other animals or figures. Other part or parts—such as the ears, eye, or under jaw—may be movable, and the ball or missile may be attached to the toy by a 65 string or elastic connection.

The parts 8, 9, 11, 12, 13, and 14 are shown by dotted lines only.

Having thus described my invention, the following is what I claim as new therein and 70 desire to secure by Letters Patent:

1. In a mechanical toy, the combination of a plane surface with a representation of a partly-fixed and partly-movable animal or figure, the movable part being pivoted to the 75 fixed part and controlled by a spring, a ball or missile, and an upright partition or fence, an opening or openings or recesses provided in said partition or fence or in the plane surface or board, the whole so arranged that on 80 pulling back the movable portion of the figure or animal and releasing the same the spring will swing it forward and strike the ball or missile, if in the correct position, into or through the said opening or openings or 85 recesses.

2. In a mechanical toy, the combination of a plane surface having the representation of the fore part of an animal, and pivoted thereto the hind part of said animal, said hind part 90 forming a striker, a spring for retaining the hind part in its elevated or projected position, and a fence attached to the plane surface and provided with an opening, all the parts being so arranged that when the hind 95 portion of the animal is withdrawn and then discharged it will swing around and strike a ball or other missile that may be in its path.

JOHN A. GOODWIN.

Witnesses:
